UNITED STATES PATENT OFFICE.

WILLIAM MILLARD, OF INDIANAPOLIS, INDIANA, ASSIGNOR TO THE E. C. ATKINS & COMPANY, OF SAME PLACE.

ADJUSTABLE BASE FOR GROOVING-SAWS.

SPECIFICATION forming part of Letters Patent No. 429,142, dated June 3, 1890.

Application filed November 4, 1889. Serial No. 329,121. (No model.)

To all whom it may concern.

Be it known that I, WILLIAM MILLARD, a citizen of the United States, residing at Indianapolis, in the county of Marion and State of Indiana, have invented certain new and useful Improvements in Adjustable Bases for Grooving-Saws, of which the following is a specification.

The object of my said invention is to provide a simple means for supporting grooving-saws, dado-cutters, &c., by which the saws may be conveniently adjusted to and from each other, and secured quickly and rigidly in the position in relation to each other desired, as will be hereinafter more particularly described and claimed.

Referring to the accompanying drawings, which are made a part hereof, and on which similar letters of reference indicate similar parts, Figure 1 is a perspective view of a pair of saws of the character named mounted on the end of a mandrel, the outside collar and nut being omitted and the saws being adjusted a considerable distance apart for the purpose of showing the parts which constitute the invention more clearly; and Fig. 2, a central longitudinal section through the same with the collar and nut in place.

In said drawings the portions marked A represent the mandrel; B B', the saws; C C', the bases on which said saws are supported, and D the collars for clamping the saws on the mandrel.

The mandrel A is or may be any ordinary saw-mandrel adapted for the purpose.

The saws B B' are or may be any saws adapted for the purpose, and are securely riveted to their respective bases.

The base C of the saw B consists of a disk somewhat larger than the collar provided with a central perforation adapted to fit closely upon the mandrel, around which is formed an inwardly-projecting annular flange c, exteriorly screw-threaded, on which is mounted a nut c', formed with a milled outer edge for convenience in operating it by hand, and having a straight outer face.

The base C' of the saw B' consists of a

disk corresponding in size to the other, formed with a cup-shaped center adapted to fit over the nut c' and against its outer face, a central perforation being provided for the mandrel, and the opposite sides of the outwardly-extending part being preferably cut away, as shown, to permit access to the nut for the purpose of operating it without the necessity of removing the saw.

The collars D are secured upon the mandrel in the usual or any desired manner, and by means of the nut D' are made to clamp the bases of the saws firmly between them and hold them to the mandrel, as will be readily understood.

The operation of my said invention is as follows: The saws being mounted upon the mandrel, as shown, and it being desirable to adjust them nearer to or farther from each other, the nut c' is turned until the space between the saws is of just the width desired, and they are then securely clamped in this position by means of the collars in the well-known manner. By this arrangement any adjustment of the saws desired can be quickly and conveniently secured.

Having thus fully described my said invention, what I claim as new, and desire to secure by Letters Patent, is—

1. The combination, with a saw or cutter-head, of a base for supporting one of the saws or cutters having an external screw-threaded flange, a nut mounted on said screw-threaded flange, and a base for supporting the other saw or cutter adapted to fit upon and bear against said nut, substantially as set forth.

2. The combination of the mandrel, the saws, the base C, formed with a screw-threaded collar c, the nut c', mounted thereon, and the base C', formed cup-shaped to fit over and against said nut, opposite sides thereof being cut away to permit said nut to be operated without removing said base, substantially as set forth.

3. The combination of the mandrel A, the saw B, securely riveted to the base C, said base C provided with the external screw-

threaded flange *c*, the nut *c'*, mounted thereon, a saw *B'*, securely riveted to the base *C'*, said base *C'* formed to fit around and against said nut, and the collars *D*, arranged to bear 5 against said bases *C* and *C'* to securely clamp them in any position desired, substantially as set forth.

In witness whereof I have hereunto set my hand and seal, at Indianapolis, Indiana, this 30th day of October, A. D. 1889.

WILLIAM MILLARD. [L. S.]
